UNITED STATES PATENT OFFICE.

FRANCIS MARION WATSON, OF COLUMBIA, TENNESSEE, ASSIGNOR OF
ONE-THIRD TO FRANK H. SMITH, OF SAME PLACE.

AXLE-SKEIN.

SPECIFICATION forming part of Letters Patent No. 369,142, dated August 30, 1887.

Application filed April 18, 1887. Serial No. 235,163. (No model.)

To all whom it may concern:

Be it known that I, FRANCIS MARION WATSON, a citizen of the United States, residing at Columbia, Tennessee, have invented a new and useful Improvement in Axle-Skeins, of which the following is a specification.

My invention relates to axle-skeins, its object being to produce a cheap and efficient skein which may be easily applied by unskilled persons and with ordinary tools—such, for example, as are ordinarily found on farms.

My invention is illustrated in the accompanying drawings, in which—

15 Figure 1 is a side elevation of a portion of the axle and skein complete; Fig. 2, a longitudinal vertical section of same, and Fig. 3 a cross-section in the plane $x x$ of Fig. 2.

As clearly indicated in the drawings, the 20 skein A consists of two "half-round" strips of cast-iron or steel, $a a$, merged at the outer end in a "tip," b , from which projects a stud, c , adapted to receive a nut, d , which may be threaded upon the stud or held by a pin, as 25 indicated by dotted lines. The two strips a , (or properly "skeins," the present device being a double skein,) with the tip b and stud c , are cast as one homogeneous piece, with flat interior faces bounding a longitudinal

30 wedge-shaped opening, and with outsides curved to the contour of the general cone of the axle, and adapted to fit the wheel-box. Near the rear end of the skein is an enlarged shoulder, e , constituting a rear abutment for the wheel-box, and the lower one of 35 the sides a may be further extended, as at f , to reach and be secured by the bolt f of the "hounds." The skein thus constructed is double and forms a facing for the upper and

40 lower sides of the axle A. As will be obvious, it may be cast without "coring," and to apply the same it is only necessary to dress off the upper and lower sides of the axle to wedge form (which may be done with a common tool, such as a "spokeshave" or "jack-knife,") to fit the opening of the skein, and to secure the skein by rivets g , passing entirely through both strips and the axle, or by wood-screws g' , (the latter shown in dotted 45 lines in Fig. 2.) The finishing or rounding of the wood to fit the wheel-boxing may be done by the same tools after the skein is secured to its position.

The advantages of my improvement reside in its cheapness, ease of application and efficiency, with reference to the application of the device under circumstances of farm use. As breakages of wagon-axles are frequent, and skilled mechanics are often remote and inaccessible, my invention is adapted to supply a needed want and enable the farmer or teamster to prepare the axle and fit the skein with great facility with tools ordinarily at hand and without recourse to a wagon-shop or a skilled workman; and in case of breakage on the road an entire axle may be made and fitted with ease from timber or rails at hand near by.

The wedge-shaped opening between the sides may be brought to a sharper angle toward the tip b , if desired, as indicated by dotted lines in Fig. 2, in order to give increased strength toward the outer end of the axle.

The skein is to be furnished complete as an article of manufacture and sale as cast, with only such smoothing as may be given with a rough file, with nut held by screw-threads or by a pin, as found desirable, and pierced for the insertion of the holding-rivets g or screws g' .

I claim as my invention and desire to secure by Letters Patent of the United States—

1. As a new article of manufacture, the improved axle-skein A', consisting of the two segmental conical strips $a a$, merging in the solid tip $d c$, and provided at the rear with the circular shoulder $e e$, said strips bounding a flat wedge-shaped opening to receive the axle A, substantially as set forth.

2. As a new article of manufacture, the improved axle-skein A, consisting of the segmental conical strips $a a$, merging in the solid tip $d c$, provided at the rear with circular shoulders $e e$ and bounding a flat wedge-shaped opening, the under one of said strips being extended beyond the upper one to engage with the bolt of the hounds, substantially as set forth.

In testimony whereof I have hereunto set my hand in the presence of two subscribing witnesses.

FRANCIS MARION WATSON.

Witnesses:

JOHN A. ENGLE,
R. C. GANT.
